GRINDING MACHINE

Arthur Scrivener, Birmingham, England

Application January 15, 1937, Serial No. 120,708
In Great Britain February 14, 1936

3 Claims. (Cl. 51—103)

This invention is for improvements in connection with grinding machines of the kind in which the work-piece is supported between centres and is mechanically rotated in pressure contact with a rotating grinding wheel.

5 The object is to provide, in a grinding machine of this kind, a means of generating screw-threads or other helical surfaces of a high degree of accuracy and finish, or of correcting such surfaces after generation by a less accurate method or after a hardening or like operation, and of thereby facilitating the continuous output necessary in the repetition grinding of screw-threaded bolts, studs, and the like.

10 According to the present invention, in a grinding machine of the kind referred to, the centred work-piece is correctly aligned in relation to annular serrations on the grinding wheel by means of a universally adjustable control finger which contacts with the helical surface either of the work-piece or of a master former rotatable between centres in axial alignment with the work-piece centres, said control finger serving also to traverse the rotating work-piece across the face 20 of the grinding wheel at a rate governed by the speed of rotation of the work-piece and by the pitch of said helical surface.

In order that the invention may be clearly understood and readily carried into practice, reference may be had to the appended explanatory drawing, in which:

Figure 1 is a front elevation, and Figure 2 is a plan, of such parts of a grinding machine as are necessary to illustrate the invention.

35 Figure 3 is a similar plan illustrating a modified form of the invention.

Figure 4 is an end elevation of a detail herein-after referred to.

Similar letters refer to similar parts throughout the several views.

In a convenient method of carrying the invention into effect, as illustrated in Figures 1 and 2 and as applied by way of example to a grinding machine of the kind referred to for the correction of screw-threads initially formed upon bolts, studs, and the like by a rolling or other operation, the work-piece *a* is mounted between a pair of centres *b* of which one is adjustable as at *c* for varying lengths of work and is spring-loaded as at *d* so as to support the work-piece *a* but leave it free to rotate, the centres being mounted in anti-friction bearings. The headstocks *e* carrying the centres *b* are mounted on a table *f* which slides freely on anti-friction bearings *g* on the bed *h* of the machine in the

direction of the axis of the work-piece *a*. At right angles to the slide table *f* is arranged another slide carrying the rotatable grinding wheel *i*, which therefore is capable of movement at right angles to the axis of the work-piece *a*, this movement determining the size of the work-piece *a* diametrically. The face of the grinding wheel *i* is formed with annular serrations disposed at right angles to the axis of the work-piece *a* and adapted to produce the desired form upon the work-piece *a*, which is rotated by a backing wheel *j* mounted either on a pivoted arm or on a slide so that it can be spring-loaded or otherwise urged towards the work-piece *a* so as to drive it by frictional contact. The 15 backing wheel *j* is geared to an electric motor or other source of power so as to be driven at a speed which imparts a suitable peripheral velocity to the work-piece *a*. Attached to the grinding wheel head is an arm *k* carrying a control finger *l* which abuts radially on the top of the work-piece *a*, this finger *l* being spring-loaded and being universally adjustable in relation to the work-piece *a*, that is to say, it has a fine micrometer adjustment in directions parallel to the axis of the grinding wheel *i*, and is also adjustable in two planes at right angles to the grinding wheel axis to suit various diameters of work-piece and grinding wheel, the control finger *l* being also rotationally adjustable 20 in its bearing.

In the operation of this form of the machine, the grinding wheel *i* is first withdrawn either manually or automatically, taking with it the control finger *l*. The work-piece *a* is then inserted between the centres *b*, and the backing wheel *j* is brought into contact so as to rotate the work-piece. The grinding wheel *i* is then brought up to the work, the control finger *l* contacting with the work-piece *a* and aligning it 25 with the serrations on the wheel *i*, which is now in its grinding position. It will be seen that the effect of the control finger *l* engaging with the initially formed screw-thread on the rotating work-piece *a* is to cause the slide *f* which carries the work-piece to travel across the face of the grinding wheel *i* for the grinding operation, at a rate governed by the speed of rotation of the work-piece *a* and by the pitch of the thread thereon. Pieces having a threaded length 30 not exceeding the width of the grinding wheel *i* will be completed in a little more than one revolution, whilst any longer piece will revolve until the whole of its threaded surface has passed the wheel *i* or the control finger *l*.

As an alternative to the adjustable mounting of the grinding wheel i , the grinding wheel head may be stationary and the whole of the other mechanism be arranged to slide in a direction at right angles to the axis of the work-piece a . Moreover the complete slide unit may be duplicated so as to provide a series of loading and operating stations, the work being loaded at one station whilst it is operated on at another, and the change of stations being effected either manually or automatically.

In another method of carrying the invention into effect, as illustrated in Figure 3 and as applied by way of example to a grinding machine of the kind referred to for the generation and finishing of screw-threads upon bolts, studs, and the like, the work-piece blank a is mounted between one pair of centres b , and a master former m is similarly mounted between another pair of centres b' , the two pairs of centres b and b' being disposed in axial alignment, and both the work-piece a and the former m being of the same diameter. The work-piece a and the former m are rotated by separate backing wheels j and j' which are independently urged forward to provide a frictional drive at the same speed both for the work-piece a and for the former m . The face of the grinding wheel i is formed with annular serrations disposed at right angles to the axis of the work-piece a and adapted to produce the desired form on the work-piece a . A universally adjustable control finger l as hereinbefore described is attached to the grinding wheel head by a carrier arm k so as to be adapted for engagement with the screw-thread on the master former m .

In the operation of this modified form of the machine, the machine is loaded as hereinbefore described with reference to the first form of the invention, and it will be seen that as the control finger l is in engagement with the master former m rotating at the same speed as the work-piece a , this causes the work-piece a to travel across the face of the grinding wheel i , thus generating the desired screw-thread and thereby reproducing the form of the master m on the blank a , one or more revolutions being required to complete the piece. When it is required to pass the work through the machine more than once, for example for the production of a highly accurate finish, a second control finger l' may be provided, this operating in association with the screw-thread generated on the work-piece a and being adjustable both in relation to the primary control finger l and to the serrations on the grinding wheel i , so as to assist in re-positioning the work-piece a on the grinding wheel i for the secondary grinding operation.

It will be appreciated that work with an interrupted surface can be ground, provided that a continuous surface is available at some part or other so that the backing wheel j can rotate the work-piece. For example, screwing taps may be treated by arranging the backing wheel j against the shank of the tap and by adjusting the diameter of the master former m to suit. For this type of work, when a second pass is required, the second control finger l' may be extended laterally as shown in Figure 4 so as to bridge the flutes a' of the work-piece a and engage two lands at the same time.

I claim:

1. In a grinding machine of the kind described, for the correction of screw-threads and other helical surfaces, the combination of an annularly serrated grinding wheel, a pair of centres adapted to support the work-piece, a backing wheel adapted to rotate the work-piece between said centres in pressure contact with the grinding wheel, and a universally adjustable control finger adapted to abut on the helical surface of the work-piece, said finger ensuring that the screw-threads on the centred work-piece are correctly aligned in relation to the annular serrations on the grinding wheel, and serving also to traverse the rotating work-piece across the face of the grinding wheel at a rate governed by the speed of rotation of the work-piece and by the pitch of the helical surface.

2. In a grinding machine of the kind described, for the generation of screw-threads and other helical surfaces, the combination of an annularly serrated grinding wheel, a pair of centres adapted to support the work-piece, a backing wheel adapted to rotate the work-piece between said centres in pressure contact with the grinding wheel, a helically surfaced master former, a pair of centres adapted to support said master former in axial alignment with the work-piece, a backing wheel adapted to rotate the master former between said centres at the same speed as the work-piece, and a universally adjustable control finger adapted to abut on the helical surface of the master former, said finger ensuring that the centred work-piece is correctly aligned in relation to the annular serrations on the grinding wheel, and serving also to traverse the rotating work-piece across the face of the grinding wheel at a rate governed by the speed of rotation of the master former and by the pitch of the helical surface thereon.

3. In a grinding machine of the kind described, for the generation of screw-threads and other helical surfaces, the combination of an annularly serrated grinding wheel, a pair of centres adapted to support the work-piece, a backing wheel adapted to rotate the work-piece between said centres in pressure contact with the grinding wheel, a helically surfaced master former, a pair of centres adapted to support said master former in axial alignment with the work-piece, a backing wheel adapted to rotate the master former between said centres at the same speed as the work-piece, a universally adjustable control finger adapted to abut on the helical surface of the master former, and a second control finger adapted to abut on the helical surface generated on the work-piece, the first-mentioned control finger ensuring that the centred work-piece is correctly aligned in relation to the annular serrations on the grinding wheel, and serving also to traverse the rotating work-piece across the face of the grinding wheel at a rate governed by the speed of rotation of the master former and by the pitch of the helical surface thereon, and the second control finger serving to facilitate the correct realignment of the screw-threads generated on the centred work-piece in the event of a secondary grinding and finishing operation being required.
